YARN PACKAGE

William E. Mahoney, Pawtucket, R. I., assignor
to Premier Thread Company, a corporation of
Rhode Island

Application November 15, 1938, Serial No. 240,490

1. Claim. (Cl. 242—161)

This invention relates to a spool for packaging thread and has for one of its objects to prevent the thread on the spool from spilling over the head and breaking as a consequence of such spilling.

Another object of the invention is to provide for the catching of the thread on a surface which will support the same and prevent the thread from continued movement which is not caught would eventuate in the thread sliding over the head of the spool.

With these and other objects in view, the invention consists of certain novel features of construction, as will be more fully described, and particularly pointed out in the appended claims.

In the accompanying drawing:

Fig. 1 is an elevation showing a spool with thread wound thereon;

Fig. 2 is a sectional view with the thread omitted;

Fig. 3 is a sectional view showing the two parts of the spool;

Fig. 4 is the sectional line 4—4 of Fig. 2;

Fig. 5 is a sectional view of a modified form of a spool;

Fig. 6 is a different form of modification;

Fig. 7 is an elevation of the spool showing the grain in the wood of the two different pieces; and

Fig. 8 is a sectional view showing a different modification.

Spools having single heads are in many instances formed with a conical head so that the package of thread on the spool may have a conical formation which will retain itself in position without the necessity of providing a second head. Such spools are usually operated with their axis vertical (although in some instances this axis may run in a horizontal position). When a spool operates with its axis vertical on a sewing machine, or the like, the vibration or jiggling of the sewing machine will cause the spool to vibrate and lift on its axis. The thread on the spool will frequently, when a bit of slack occurs, slide down the vertical outer surface of the package and conical surface of the head and lodge beneath the spool and there become caught so that the pull on the thread will cause the thread to break. This is a very real difficulty encountered in the operation of machines using this type of spool.

Various manners and various attempts have been made to solve the problem. I have, however, approached the problem differently than previous attempts in an effort to solve the same and have, in a very simple manner, changed the spool itself so that rather than trying to prevent the thread

from movement toward the head, I catch the thread after it has slid down and support it so it cannot get below the spool or in any crevices to catch and be broken, and this I accomplish by providing a flange on the head of the spool which will present a surface either in a plane at right angles to the axis or will incline inwardly so that any thread which drops on this flange will be supported and cannot get below the spool; and the following is a more detailed description of the present embodiment of this invention, illustrating the preferred means by which these advantageous results may be accomplished:

With reference to the drawing, 10 designates a shank of the spool and 11 the head thereof. 15 This head consists of conical portion 12 presenting an inclined surface 13 to shape the package of thread 14 which may be wound thereon. I form on the head 11 a flange 15 which extends outwardly, radially, from the shank of the spool. 20 This flange presents its shank-side surface either at right angles to the axis of the spool as shown at 16 in Fig. 5 or inclined inwardly as shown at 16' in Figs. 1, 2, 3 and 6, and by the provision of this flange 15 and this supporting surface 16 and 25 16', any thread 17 which may drop from the package 14 will be caught and supported by this surface 16 and 16' and prevented from spilling by sliding beneath the head of the spool and there becoming caught and broken.

While I may form the parts which I have just mentioned all in one piece as shown in Fig. 6, it is usual that when the spool is turned from wood with the grain running generally axially of the shank, that chipping of the flange is liable to occur during the shipping or rough handling and, accordingly, I preferably form the shank 10 in one piece as illustrated in Fig. 3 and the head in another piece 11 in Fig. 3 with the grain of the wood in the shank running axially of the 30 shank and the grain of the wood in the head running at right angles to the axis of the shank and in this manner chipping of the flange is very much reduced. It may be, however, that where the material used is not of the grain characteristics of wood that a single-piece product will be 35 satisfactory.

In Fig. 8 I have illustrated the shank 18 and conical head 11 as formed all in one piece as is a usual construction and have provided an additional piece 19 secured to the under surface of the head by cement 18 which piece may be of some material different than the wood of the shank and head and may, for example, be fibre or cardboard. In shipping, however, spools provided 40 45 50 55

with a cardboard member to form a flange have not proven satisfactory from the standpoint of withstanding rough handling, although from the standpoint of operation of the invention, if the portion 19 be not damaged the member 19 may exist in cardboard as well as other materials, provided the joint 21 may be made to prevent the occurring of a crevice which is an added factor to guard against in a construction so formed and which is not present at 20 in Fig. 5 or the other figures heretofore described.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

20 A conical end yarn package comprising a

cylindrical winding of yarn about a single-headed spool having an individual shank portion with an adjoining individual conical head portion provided with a relatively short taper abruptly increasing in diameter from its juncture with the shank portion and extending throughout the diameter of the winding of yarn, said head portion being provided at the termination of its taper with a flange extending outwardly beyond said winding of yarn, said flange having a surface on the shank side thereof so formed and arranged as to prevent the movement of yarn on the outer winding of the package from sliding thereover when the package is in use in an upright position, said head and shank being of separate pieces of wood with the grain of the wood in said shank extending axially thereof and the grain of the wood in the head extending laterally of the axis of the shank to minimize splitting of said flange.

WILLIAM E. MAHONEY. 20
